(57) **CLAIM**

The ornamental design for a flexible security bag, as shown and described.

DESCRIPTION

FIG. 1 is a perspective view of the flexible security bag with its flap in a closed position showing my new design;
FIG. 2 is a front view thereof;
FIG. 3 is a top view thereof;
FIG. 4 is a back view thereof;
FIG. 5 is a bottom view thereof;
FIG. 6 is a right side view thereof;
FIG. 7 is a left side view thereof; and,
FIG. 8 is a front view of FIG. 1 with the flap in its open position.

The broken lines, and the unshaded surfaces within, illustrate portions of the flexible security bag and form no part of the claimed design.
